UNITED STATES PATENT OFFICE

ALLAN A. ADAMSON, OF ROCHESTER, NEW YORK, ASSIGNOR, BY MESNE ASSIGNMENTS,
TO AUTOKRAFT BOX CORPORATION, OF LIMA, OHIO, A CORPORATION OF DELAWARE

WRAPPING AND LINING MEANS FOR BOXES

Application filed December 6, 1928. Serial No. 324,152.

The present invention relates to wrapping and lining means for boxes, and an object of the invention is to provide for combining the wrapping and lining means in such manner that the wrapping and lining of a box may be effected by machinery with a minimum number of operations. Another object of the invention is to provide lining means for the inner faces of the wall of a box in the form of extensions on those sections of the wrapping means covering the outer faces of the vertical walls.

To these and other ends, the invention consists of certain parts and combinations of parts all of which will be hereinafter described: the novel features being pointed out in the appended claims.

In the drawings:

Fig. 1 is a perspective view of the box to be lined;

Fig. 2 is a plan view of one blank for covering the inner and outer faces of the front and end walls of the box;

Fig. 3 is a plan view of a blank for covering the inner and outer faces of the rear wall of the box;

Fig. 4 is a longitudinal vertical section of a covered box;

Fig. 5 is a transverse vertical section of a covered box; and

Fig. 6 is a perspective view of a covered box.

The box body illustrated is of the form commonly employed in cigar boxes comprising a bottom wall 1, front and rear walls 2 and 3, and end walls 4 projecting above the front and end walls to receive the lid or cover between them. The bottom wall 1 has, in this instance, a paper lining 5 which is applied to the sheet from which the bottom is cut before the bottoms are formed therefrom.

The wrapping means, in this instance, comprises four sections 6, 7, 8 and 9, the sections 6, 7 and 8 being formed in one blank and being arranged end to end for covering the two end walls and the front of the box, the section 7 for covering the front wall being shorter in height than those portions covering the end walls. The sections for covering

the end walls as well as the section for covering the front wall have portions 11 which cover the upper horizontal edges of such walls. The portion 11 on the section 7 is spaced from opposite ends of said section by slits 11^a to provide portions 11^b for covering the edges of the adjacent end walls above the front wall. End or corner flaps 12 are provided on the end sections 6 for being adhesively secured to the outer face of the rear wall of the box adjacent the corners and having extensions 12^a for covering the edge of the adjacent end wall above the rear wall. Each section 6, 7 and 8 has at its bottom edge a flap extension 13 which will serve to edge the under face of the bottom wall of the box by being adhesively secured thereto. The section 9 of the wrapping means is applied to the rear wall after the other blank is applied and has at its lower edge a flap 18 to be adhesively secured to the bottom of the box. This section also includes a portion 19 for covering the upper horizontal surface of the rear wall.

The lining means includes sections 14, 15, 16 and 17 which are in the form of extensions on the upper edges of the sections 6, 7, 8 and 9 respectively. Each of the extensions 14, 15 and 16 is less in width than its respective sections 6, 7 or 8, as the lengths of the inner faces of the walls to which these sections are applied is less than the lengths of the outer faces, with this exception, that the extensions 14 and 16 are projected at their ends at 20 to cover the inner faces of the end walls above the front and the rear vertical wall. The extension lining section 20 may be the same in width as the section 18 because the latter is not required to be as wide as the rear wall due to the fact that the corner flaps 12 cover portions of the rear walls.

It is preferred to apply first the blank shown in Fig. 2 covering the front walls and the end walls both on the outside and the inside and then to apply the blank shown in Fig. 3 to cover the rear wall both inside and out. The extensions 14, 15, 16 and 17 are long enough to extend a short distance onto the

bottom of the box to cover the bottom corners and as the bottom is lined preferably with the same material as that of which the blanks are formed, the entire box has a lined appearance.

What I claim as my invention and desire to secure by Letters Patent is:

1. Combined wrapping and lining means for the side and end walls of a box in which the end walls project upwardly above the side walls, comprising a blank embodying three wrap sections connected end to end, for covering the end walls and a side wall, each of said sections having a portion for covering the upper edge of the corresponding wall, and the central section having extensions for covering the adjacent upwardly projecting end edges of the end walls, corner flaps at the opposite ends of the blank, for attachment to the outer face of the other side wall, and having extensions for covering the adjacent upwardly projecting end edges of the end walls, a liner extension on each wrap section, for covering the inner face of the corresponding wall, and a second blank embodying a wrap section for covering the outer face of the other side wall between the corner flaps and in lapping relation to said flaps, said last-mentioned section having a portion for covering the upper edge of the corresponding wall, and a liner extension on said last-mentioned section, for covering the inner face of such corresponding wall.

2. Combined wrapping and lining means for the side and end walls of a box in which the end walls project upwardly above the side walls, comprising a blank embodying three wrap sections connected end to end, for covering the outer faces of the end walls and a side wall, each of such sections having a portion for covering the upper edge of the corresponding wall, the central section being of less height than the end sections and having extensions for covering the adjacent upwardly projecting end edges of the end walls, corner flaps at the opposite ends of the blank and projecting from the end wrap sections, for attachment to the outer face of the other side wall, and having extensions for covering the adjacent upwardly projecting end edges of the end walls, and three liner sections spaced apart and forming extensions of the respective wrap sections, for covering the inner faces of the corresponding walls, the liner sections for the end walls having extensions at their opposite ends, adjacent the corresponding wrap sections, for covering the inner faces of the end walls above the side walls, and a second blank embodying a wrap section for covering the outer face of the other side wall between said corner flaps and in lapping relation with said flaps, said last-mentioned wrap section having a portion for covering the upper edge of the corresponding

side wall, and a liner section forming an extension of said last-mentioned wrap section, for covering the inner face of such corresponding side wall.
